UNITED STATES PATENT OFFICE

2,256,447

REFRIGERATOR LATCH

William O. Burke, Rockford, Ill., assignor to National Lock Co., Rockford, Ill., a corporation of Delaware

Application May 5, 1939, Serial No. 271,851

5 Claims. (Cl. 292—223)

This invention has as its object the provision of improvements in a refrigerator latch, one of these improvements being the arrangement of a bolt operating lever and formations on the latch casing adapted to receive the hasp of a padlock to block movement of the operating lever and thus lock the latch.

Another object is the provision of a latch having a bolt operating lever which fits into an offset yoke on a handle, the lever having a transverse pin with rollers thereon to engage the forks of the yoke for movement of the lever when the handle is turned, the yoke portion also serving as a guide means for the lever.

Another object is the provision of a stamped bolt which is pivotally mounted on the casing and which is provided with an attaching pin pivotally engaging an end of the operating lever, the stamping having a tongue turned inwardly and slotted to fit around an end of the lever and limit the movement of the latter in cooperation with the aforesaid forked formation on the operating handle.

Another object is the provision of an adjustable keeper for the bolt which includes a bracket recessed to receive a keeper piece which is adjustably secured thereto by a single screw, the keeper and bracket having interlocking formations coacting with the screw to secure the keeper in a position of adjustment.

Still another object is the provision of a novel keeper mechanism including a roller keeper and means for adjustably mounting the same with respect to the bolt, and a bolt having a keeper formed thereon for camming and locking cooperation with the roller keeper.

Other objects, advantages and economies residing in the invention relate to certain details of construction, as well as the arrangement and mode of operation of the parts of the illustrative embodiment described hereinafter in view of the annexed drawings, in which:

Fig. 1 is a perspective view of the latch and keeper;

Fig. 2 is a horizontal section of the latch in closed position as seen in the direction of line 2—2 of Fig. 1;

Fig. 3 is a vertical section along line 3—3 of Fig. 2;

Fig. 4 is a fragmentary vertical section through the hasp-receiving formations on the housing, looking in the direction of line 4—4 of Fig. 3;

Fig. 5 is a vertical sectional detail through the bolt structure, looking in the direction of line 5—5 of Fig. 2;

Fig. 6 is a horizontal section through a modified form of the latch structure including the adjustable roller keeper and keeper bolt;

Fig. 7 is a perspective of the adjustable roller keeper;

Fig. 8 is a perspective of the keeper bolt with portions of the operating mechanism; while

Fig. 9 is a rear elevation of the latch as viewed in the direction of line 9—9 of Fig. 6.

10 The preferred embodiment of the invention shown in Fig. 1 includes a cast housing 10 adapted for attachment by bolt means 11 to a refrigerator door 12, there being an operating handle 13 mounted on a pintle 14 within the housing. A rocking bolt structure 15 is mounted on a pintle 16 at an end of the housing and is equipped with a roller 17 secured by pin means 18 extended between opposite arms 19 of the bolt unit, and in a position for engagement with 20 a hook-shaped keeper 20 secured to the jam of the door by means such as the bolts 21 extended through the base of a mounting bracket 22.

Means for operating the bolt, as shown in Figs. 2 and 3, includes a reciprocable operating lever 25 pivotally attached at its left-hand end to a pin 26 secured between the opposite sides 19 of the bolt unit. The opposite end of the lever is provided with an elongated slot 27 which embraces a pin 28 so that the lever may shift back and forth from right to left and rock the bolt unit 15 into and out of latching engagement with its keeper 20. The bolt lever is normally urged into latching position by a spring 29 mounted on the lever with one of its ends bearing against the pin 28 and the opposite end bearing against shoulder formations 30 formed on the lever. Thus, the bolt is pivoted in an anti-clockwise direction into latching position as seen in Fig. 2.

40 The operating handle 13 (Fig. 2) has an offset bifurcated end including opposite arms or forks 31 and 32 which lie on opposite sides of the lever 25 and which are curved along their inner edge portions 33 for bearing engagement with rollers 34 mounted on opposite sides of the lever 25 by a headed pin 35. A suitable spring 36 is mounted on the pintle 14 on the handle within the housing to urge the handle into a normal position with the yoke portions 31—33 bearing against the roller 34 on the bolt operating lever, as represented in Fig. 2.

In order to operate the latch from the condition shown in Fig. 2, the handle 13 is moved outwardly of the housing so as to cause the bifurcated portions 31—32—33 to bear against the

rollers 34 and shift the lever 25 toward the right against the effort of the spring 28, thus pivoting the bolt unit in a clockwise direction away from the keeper 50.

One of the features of the latch structure is the provision of a locking tail 48 at the end of the lever 25 and which is adapted to shift beneath a pair of registered lock hasp receiving openings 41 (Fig. 3) cast into an extension 42 on the housing. As illustrated in Fig. 1, the hasp portion 43 of a padlock may be passed through the openings 41 to block the movement of the tail portion 48 of the operating lever and thus lock the latch against operation.

This arrangement is especially effective because 15 the portion 42 in which the hasp-receiving openings 41 are formed is compactly arranged and of minimized dimension so as to afford the least possible leverage to an attempt to tear the lock hasp through the wall portions surrounding the 20 openings 41, the minimized size of the extension 42 also tending to defeat breakage by blows directed particularly against this part of the housing.

The bolt unit 15 is constructed in an especial manner by stamping, from a single piece of stock, the opposite wall portions 19 joined by an intermediate or connecting wall portion 19a (Figs. 1, 2 and 5). This intermediate wall portion has an extended tongue part 19b which is 25 bent inwardly between the opposite wall portions 19 and slotted as at 19c (Figs. 2 and 5) to fit over the end portion of the operating lever adjacent the pin 26 and provide a means for limiting the lateral movement of the lever relative to the pins 26 and 28 upon which it is mounted. This same limiting support is afforded, in part, by the opposite fork arms 31 and 32 on the handle. In addition to its supporting function, the inwardly projecting tongue 40 19b adds strength to the bolt structure and closes off a considerable portion of the same to access from the outside of the latch, that is, it closes up a substantial portion of the opening occupied by the bolt unit in the housing.

The keeper is adjustable, being formed with a base portion 20a of substantially rectangular outline (Figs. 1, 2 and 3) adapted to slide or shift in a recessed portion 22a in the bracket 22, the confronting surfaces of this recessed portion and the base portion of the keeper being serrated as at 22b to interlock in cooperation with a screw 37 which threads into the bracket through the base portion of the keeper from the inside of the latter, that is, behind the keeper where it will be inaccessible so long as the bolt is engaged with the latter. By loosening the screw 37, the base portion of the keeper may be freed from interlocking engagement with the serrations in the bracket and the keeper may 50 be shifted inwardly and outwardly to meet the requirements of various installations.

In Fig. 6 there is illustrated a modification of the keeper and bolt mechanism. The basic latch operating mechanism is the same as that heretofore described in so far as a handle member 13 is arranged to actuate an operating lever 25 through the medium of the offset yoke means bearing against roller means 34.

The principal difference characterizing the 70 modification resides in the provision of a keeper bolt 50 pivoted on the same pintle 16 as was employed in the structure of Fig. 1, for example. The bolt is provided with a horizontally extending slot 51 into which the end of the op-

erating lever 25 projects for pivotal engagement with a pivot pin 26a corresponding to the pivot 26 in the arrangement of Fig. 2, while the slot 51 corresponds functionally to the slot 19c formed in the tongue part of the hollow bolt.

The bolt 50 is oscillated by the lever 25 responsive to manipulation of the handle in the manner described in operating the latch of Fig. 1. The bolt 50 (Fig. 8), however, is preferably a solid casting, and near its end opposite its pivotal mounting 16, it is provided with a keeper 52 having a cammed surface portion 53 adapted for locking cooperation with a keeper roller 54 (Figs. 6 and 7) rotatable on a pin 55 secured between opposite ears 56 on a base portion 57.

The base portion 57, like the base portion 20a of the device of Fig. 2, is adjustably fitted into the grooved portion 58 of a keeper mounting bracket 59, a single screw 60 being projected through an enlarged opening 61 in the base portion and threaded into the mounting bracket, the opposing surface portions of the bracket and the base member being serrated as at 62 for interlocking engagement of the keeper and bracket when the screw 60 is turned up. By loosening the screw 60, the interlocked serrations are freed so that the base member and roller may be slid into and out of the mounting bracket for appropriate positioning relative to the keeper member 52 on the bolt 50.

In operation the latch bolt 50 is normally projected so that when the door is slammed the cam portion 53 will strike the roller 54, causing the bolt to recede against the pressure of spring 28 until the keeper nose projects behind the roller as shown in Fig. 6 by reaction of the spring.

One of the advantages of this latter arrangement of cooperating keeper bolt and roller keeper resides in the fact that the roller will take up some of the initial shock and hence relieve some of the stress on the adjustable base structure 57 when the bolt strikes home.

The objects and advantages of the invention may be realized in other forms of construction and arrangements of parts, and the specifically described structure herein is not to be construed as a limitation upon the scope of the invention except as may be provided in the appended claims.

Having thus described my invention, what I claim as new and desire to protect by Letters Patent is:

1. In a latch, a recessed bolt mounted for pivotal movement into and out of latching position, a link pivotally connected at one of its ends to pin means in a recessed part of said bolt, said bolt having a tongue portion slotted to fit around said end portion of the link near said pin means to prevent shifting movement of the link along the pin means, and means for effecting movement of said link back and forth for the purpose of pivoting the bolt.

2. In a latch, a bolt including opposite wall portions joined by an intermediate wall portion, a part of which is turned inwardly between the opposite wall portions, keeper engaging means secured between said opposite wall portions near one end of the bolt, means arranged near an opposite end of the bolt pivotally mounting the same for movement into and out of engagement with a keeper, a member arranged for movement back and forth and having an end portion pivotally connected to pin means between said opposite wall portions of the bolt, said end portion being fitted into a notch formed in the inwardly turned

part of the intermediate wall portion whereby said member is prevented from shifting on the connecting pin means thereof, said member having an elongated slot remote from its attachment with the bolt and through which extends a mounting pin, and coacting spring and handle means for effecting movement of said member to pivot the bolt into and out of latching position.

3. In a latch, in combination, a pivoted bolt including opposite wall portions joined by an intermediate wall portion, part of which is turned inwardly between said opposite wall portions, a member pivotally connected at one of its ends to pin means disposed between said opposite wall portions of the bolt, said end portion projecting into a slot formed in said inwardly turned part of the intermediate wall portion whereby to limit shifting movement of said member transversely of its direction of reciprocation, said member being provided with an elongated slot remote from said bolt, a guide pin extending through said elongated slot, spring means normally urging said member in a direction toward said bolt to move the latter into latching position, an operating handle having a bifurcated lever arm fitted around said member and adapted to bear against laterally projecting roller means secured on opposite sides of the member by a transverse pin member secured thereto, said bifurcated portions limiting shifting movement of the member transversely of its direction of reciprocation.

4. In a latch of the type including a bolt and operating handle pivotable about parallel axes and link means interposed between the bolt and handle for reciprocation by the latter to pivot the bolt into and out of latching position, im-

- proved link means comprising an elongated member operatively connected near one end with said bolt and having an elongated slot near an opposite end, and stationary pin means extending in parallelism with the axes of the bolt and handle through said slot, means operatively interconnecting said handle with said member at a point between the ends of the latter, said member having laterally enlarged portions situated between said slot and the operative interconnection thereof with said handle, and a coil spring surrounding said member with one end bearing against said pin means and an opposite end bearing against said laterally enlarged portions, whereby to urge said member and said bolt into a normal position in a direction away from said pin means.
5. In a latch of the type including a bolt movable back and forth, a reciprocable link connected with said bolt to move the same as aforesaid, and handle means operatively associated with said link to reciprocate the latter, improved link means comprising an elongated member operatively connected near one end with said bolt and provided with a longitudinally enlarged pin slot near an opposite end, stationary pin means projecting through said slot in a direction transversely of said member, said member having laterally extending shoulder formations disposed between said slot and the connection of the member with said bolt, a coil spring surrounding said member and having one end bearing against said pin means and an opposite end bearing against said shoulder formations, whereby to urge said member and bolt into a normal position away from said pin means.

WILLIAM O. BURKE.
